Inventor.

UNITED STATES PATENT OFFICE.

FREDERICK I. DANA, OF PROVIDENCE, RHODE ISLAND, ASSIGNOR TO THE THOMAS PHILLIPS COMPANY, OF SAME PLACE.

EXPANSIBLE PULLEY.

SPECIFICATION forming part of Letters Patent No. 588,898, dated August 24, 1897.

Application filed August 27, 1895. Serial No. 604,105. (No model.)

To all whom it may concern:

Be it known that I, FREDERICK I. DANA, of Providence, county of Providence, State of Rhode Island, have invented certain new and useful Improvements in Expansible Pulleys; and I do hereby declare the following specification, taken in connection with the accompanying drawing, forming part of the same, to be a full, clear, and exact description thereof.

10 The present invention relates to that class of pulleys which are so constructed that their diameter may be increased or diminished at will and to the means for varying the diameters of such pulleys, and has for its object the construction of a pulley of the above class which may be readily applied in those relations in which expansible pulleys are employed and which may be quickly and accurately adjusted to the desired diameter without stopping the rotation of the pulley.

15 Expansible pulleys are frequently used as driving-pulleys for machines, the speed of which must be frequently varied to suit the varying conditions of the material passing through the machine, and when such pulleys have been used they have commonly been of such a character and the means for varying their diameter has been so constructed that it has been necessary to stop the rotation of 20 the pulley, and thus the operation of the machine, when the diameter of the pulley was to be varied to vary the speed of the machine, and the production of the machine thus reduced proportionally. Moreover, in such 25 cases the variation of the diameter of the pulley to produce the necessary variation in speed was necessarily a matter of guesswork and several stoppings and adjustments were frequently necessary before the exact variation in the speed required for the proper 30 operation of the machine was attained. With the present improvements, however, the diameter of the pulley may be quickly and accurately varied without interfering in any 35 way with the running of the machine to which the pulley is applied, and the means for varying the diameter of the pulley is always under the direct control of the operator, and thus the speed of the machine may be gradually and quickly changed to produce the best 40 results without stopping the machine and

the product of the machine correspondingly increased.

The invention consists in the features and combinations hereinafter described and 55 claimed.

60 The accompanying drawing shows a longitudinal section of a pulley and its operating means embodying the present improvements in their preferred form.

As shown in the drawing, the pulley A comprises any desired number of sections 1, (two only of which are shown,) provided with projecting bars or arms 2, which are adapted to slide radially in guides 3, formed on the hub 65 4. The sections 1 may be moved radially by any suitable means which is so constructed that it may be operated while the pulley is in motion and, as shown, is so moved by means of a slide 5, acting through arms 6 and toggles 70 7. The toggles 7 are formed by the arms 8 and 9, pivoted together at 10, the arms 8 being pivoted at the opposite ends to the hub 4 at 11 and the arms 9 being pivoted at their opposite ends to projections 12, formed on 75 the bars 2. The arms 6 are pivoted to the toggles 7 at 10 and to the slide 5 at 13.

The slide 5 may be operated by any suitable means under the control of the operator, which is so constructed and connected with 80 said slide that said slide may be operated while it and the pulleys are in motion, and in the drawing is shown one form of such operating means, which is as follows:

Surrounding the shaft 14, to which the 85 pulley is secured, is a non-rotatable screw-threaded member in the form of a sleeve 15, provided with a flange 16, which fits within a recess formed in the slide 5, being held therein by a collar 17, secured in the end of 90 said recess by the screws 18. An antifriction-washer 19 is interposed between the end of the sleeve 15 and the end of the recess. The sleeve 15 fits and slides within a stationary bracket or support 20 and is held 95 from rotation by a screw 21, the end of which projects into a slot formed in said sleeve. The end of the bracket 20 is counterbored to form a bearing for a screw-threaded member in the form of a nut 22, which does not rotate 100 with the pulley, but is normally stationary relative thereto. The nut 22 engages the

threads of the sleeve 15 and is held from longitudinal movement by the screws 23, which enter a groove formed in said nut. A hand-wheel 24 is secured to the nut 22, preferably 5 by being formed integrally therewith.

The operation is as follows: When the pulley A is in motion, the slide 5 rotates therewith while the sleeve 15 and the nut 22 remain stationary and through the connections described maintain said pulley at a constant diameter. If it is desired to vary the diameter of the pulley, it may be quickly and accurately done without stopping the pulley by moving the hand-wheel 24, thus causing 15 the nut 22 to move the sleeve 15 and through it the slide 5 in either direction. The movement of the slide acts through the arms 6 and toggles 7 to move the sections 1 either toward or away from the hub of said pulley, thus 20 contracting or expanding said pulley.

What I claim as my invention, and desire to secure by Letters Patent, is—

1. The combination, with an expandible pulley, of means for varying the diameter of 25 said pulley comprising a screw-threaded member normally stationary relative to said pulley, and a non-rotatable screw-threaded member operated by said former member, substantially as described.

30 2. The combination, with an expandible pulley, of means for varying the diameter of said pulley comprising a slide, a non-rotatable screw-threaded member for operating said

slide, and a rotatable nut normally stationary relative to said pulley for operating said 35 screw-threaded member, substantially as described.

3. The combination, with an expandible pulley, of means for varying the diameter of 40 said pulley comprising a slide, a non-rotatable screw-threaded sleeve for operating said slide, and a rotatable nut normally stationary relative to said pulley for operating said 45 slide, substantially as described.

4. The combination, with an expandible 45 pulley comprising radially-movable sections, of toggles connected to said sections, a slide for operating said toggles, a non-rotatable screw-threaded sleeve connected with said slide, and a rotatable nut normally stationary 50 relative to said pulley engaging said sleeve, substantially as described.

5. The combination, with a pulley provided with radially-movable sections, of toggles connected with said sections and said pulley, 55 a slide, links connected with said slide and said toggles, a non-rotatable screw-threaded member for operating said slide, and a rotatable nut normally stationary relative to said pulley for operating said screw-threaded 60 member, substantially as described.

FREDERICK I. DANA.
